PNEUMATIC BOTTLE SHOOTING GUN

Wilbur G. Sherman, San Diego, Calif.

Application October 20, 1947, Serial No. 780,777

5 Claims. (Cl. 124—11)

1

My invention relates to a pneumatic bottle shooting gun, more particularly for use in projecting beer bottles or other similar bottles for entertainment purposes and the objects of my invention are:

First, to provide a bottle shooting gun of this class which is particularly adapted for use in projecting plastic beer bottles or other similar bottles for the purpose of entertaining persons enjoying the sport of shooting;

Second, to provide a bottle shooting gun of this class which is very forceful in projecting a beer bottle or the like over a considerable distance whereby considerable excitement is created in the shooting of said gun;

Third, to provide a bottle shooting gun of this class which is adapted to project bottles base first whereby pressure exerted on the bottle is introduced at the neck end thereof preventing collapse of the bottle under reasonably high pressures exerted there against in the barrel of the bottle shooting gun;

Fourth, to provide a bottle shooting gun of this class having a barrel in which locating springs hold the bottle in certain position preliminary to the projection thereof from the gun whereby the bottle is prevented from becoming cracked or broken due to initial lateral thrust thereof in the barrel when the air pressure is suddenly applied thereto;

Fifth, to provide a bottle shooting gun of this class having a novel air inlet baffle arranged to direct the compressed air toward one side of the neutral axis of a bottle in the barrel of the gun whereby the release of compressed air in the barrel over said baffle prevents undue initial thrust on the bottle preventing breakage thereof;

Sixth, to provide a bottle shooting gun of this class having a novel poppet valve of considerable area which is very easily released from its seat due to a very slight difference in projected area on which the air pressure acts to hold the valve closed;

Seventh, to provide a bottle shooting gun of this class having a magazine and reloading sleeve which permits the gun to be fired quite rapidly whereby numerous rounds of bottles may be projected from the barrel of the gun in very rapid consecutive order;

Eighth, to provide a bottle shooting gun of this class having a novel trigger valve mechanism;

Ninth, to provide a bottle shooting gun of this class requiring only compressed air for propelling of the bottles from the gun; and

2

Tenth, to provide a bottle shooting gun of this class which is very simple and economical of construction, efficient in operation and which will not readily deteriorate or get out of order.

With these and other objects in view, as will appear hereinafter, my invention consists of certain novel features of construction, combination and arrangement of parts and portions as will be hereinafter described in detail and particularly set forth in the appended claims, reference being had to the accompanying drawings and to the characters of reference thereon forming a part of this application in which:

Figure 1 is a fragmentary top or plan view of my bottle shooting gun; Fig. 2 is a fragmentary sectional view taken from the line 2—2 of Fig. 1 showing parts in elevation to facilitate the illustration; Fig. 3 is a transverse sectional view taken from the line 3—3 of Fig. 2 showing portions of the structure fragmentarily; and Fig. 4 is an enlarged fragmentary sectional view taken from the line 4—4 of Fig. 1.

Similar characters of reference refer to similar parts and portions throughout the several views of the drawings.

The gun barrel 1, pressure cylinder 2, sleeve 3, bottle engaging springs 4 and 5, magazine 6, valve 7, air cylinder 8, plunger 9, spring 10, trigger valve casing 11, trigger 12, pistons 13 and 14, loading handle 15, trigger handle 16, counter 17, standard 18, sight 19, tubes 20, 21 and 22, and the spring 23 constitute the principal parts and portions of my bottle shooting gun.

The gun barrel 1 is a hollow tubular member having an opening 1a in the side wall thereof surrounded by the sleeve 3 which is reciprocally mounted over said gun barrel 1 as indicated by dash lines in Fig. 2 of the drawings. Rigidly connected to the outer side of the sleeve 3 is a plate spring 4 having a nib 4a extending through an opening 3a in the sleeve 3 for engagement with bottles as indicated by dash lines A in Fig. 2. The spring 5 is a plate spring secured to the inner side of the gun barrel 1 adjacent the rear edge of the opening 1a therein and this spring 5 is arranged to engage the neck end of a bottle as indicated by dash lines A for positively locating the same relatively to the nib 4a and the baffle 1b in the rear end of the barrel 1 extending in inclined relationship to substantially the middle portion of the interior of said gun barrel 1. Connected to the gun barrel 1 in adjacent relationship with said baffle 1b is the pressure cylinder 2. Reciprocally mounted in this pressure cylinder 2 is the valve 7. This valve 7 is a

slidably mounted poppet valve having a soft seat facing 7a and an external groove 7b in which the O-ring 7c is positioned. This O-ring is slideable internally of the concentric hollow cylindrical portion 2a of the pressure cylinder 2. It is to be noted that the inside diameter of the hollow cylindrical portion 2a is slightly less than the inside diameter of the gun barrel 1 adjacent to the end of which the poppet valve 7 is engaged, providing a differential area between the engaging side of the poppet valve at the facing 7a and the opposite side whereby pressure existing in the cylinder 2 forces the poppet valve 7 against the end 1c of the gun barrel 1 with certain sealing thrust in addition to the thrust of the spring 10, as shown in Fig. 2 of the drawings. The slight differential in area as hereinbefore set forth permits the poppet valve 7 to be forced away from the end 1c of the gun barrel 1 with a minimum amount of pressure. Secured to the valve 7 is a plunger shank 9a of the plunger 9 having a piston portion 9b in the air cylinder 8, internally of which the tube 22 communicates at the inner side of the piston 9b for forcing said piston outwardly and moving said poppet valve from the end 1c of the gun barrel 1. Surrounding the stem 9a of the plunger 9 is an O-ring 2b in the end of the cylinder 2. The end of the cylinder 2 internally of the hollow cylindrical portion 2a is provided with a vent 2c arranged to compensate for movement of the poppet valve within said hollow cylindrical portion 2a all as shown best in Fig. 2 of the drawings. The gun barrel 1 is mounted on the standard 18 and is supported by a spaced rail 18a secured to the gun barrel 1 by the bracket 18b near its forward end and secured to the pressure cylinder 2 near its rearward end providing clearance for the reciprocal movement of the sleeve 3 around the gun barrel 1 when loading the bottles from the magazine 6. The loading handle 15 is rigidly connected to the sleeve 3 and extends backwardly through the slide bracket 15a secured to the cylinder 2 and the handle portion 15b of the loading handle 15 is arranged to be grasped by one hand of the operator while the opposite hand of the operator grasps the trigger handle 16 and places his trigger finger over the end 12a of the trigger 12. The trigger 12 is mounted in the trigger casing 11 and secured on the shank 12b of the trigger 12 are the pistons 13 and 14 arranged in spaced relationship in the cylinder 11 as shown best in Fig. 4 of the drawings. The spring 23 surrounding the shank 12b tends to hold the pistons 13 and 14 in the position as shown in Fig. 4 of the drawings wherein the air inlet 20 communicates directly with the tube 21 which feeds air under pressure to the inside of the pressure cylinder 2. The tube 22 communicating with the interior of the air cylinder 8 at one side of the piston 9b communicates with the air supply tube 20 when the trigger 12 is pulled backwardly compressing the spring 23 and moving the pistons 13 and 14 against compression of the spring 23 whereby the piston 13 passes the tube 22 and the piston 14 passes the tube 21 shutting off the supply of air to the pressure cylinder 2 and diverting it to the air cylinder 8. These pistons 13 and 14 are provided with external O rings arranged to prevent escape of air therearound and the cylinder 11 at its opposite ends is provided with vent openings 11a and 11b arranged to compensate for entrapment of air in the ends of the cylinders adjacent the pistons 13 and 14 respectively.

The magazine 6 is a channel shaped in cross section inclined member communicating with the opening 1a in the side wall of the gun barrel 1 outwardly of the sleeve 3 as shown best in Figs. 2 and 3 of the drawings. The standard 18 is provided with a pair of telescopic tubular portions 18c and 18d mounted on an enlarged base 18e so that the elevation of the gun may be changed by telescopically adjusting the tubes 18c and 18d and fixing them together with a bolt 18f which may be placed in any one of a plurality of holes in the tubes 18c and 18d. The operation of my bottle shooting gun is substantially as follows:

15 The magazine 6 is filled with bottles as indicated by dash lines A in Fig. 3 of the drawings, and these bottles A gravitate to the sleeve 3 which covers the opening 1a in the gun barrel 1. When the sleeve 3 is forced forwardly into the dash line position as shown in Fig. 2 of the drawings by means of the handle 15b, one of the bottles A gravitates through the opening 1a into the gun barrel 1 then the operator forces the sleeve backwardly between the bottle in the gun barrel 1 and the adjacent bottle in the magazine 6. The radius at the periphery of the butt end of the bottles permits the sleeve 3 to pass therebetween quite readily. When the sleeve 3 is positioned in the solid line position as shown in Fig. 2 of the drawings, the nib 4a of the spring 4 holds the bottle A downwardly in the gun barrel 1 as shown in Fig. 2 of the drawings, and the spring 5 engages the neck thereof holding the same forwardly in the barrel in spaced relation from the baffle 1b which extends to substantially the axis of the barrel. The operator in shooting the bottle pulls the trigger 12a which slides the pistons 13 and 14 beyond the tubes 21 and 22, opening the inlet of compressed air from the tube 20 to the tube 22 which forces the piston 9b of the plunger 9 backwardly carrying the poppet valve 7 away from the end 1c of the gun barrel 1 permitting the air in the pressure cylinder 2 to be exhausted into the gun barrel 1 and force the bottle A outwardly thereof at fairly high velocity. As each bottle emerges from the gun barrel 1, the counting device 17 registers the bottle numerically. It will be noted that when the poppet valve 7 is pulled backwardly, the required force to move the same away from the end 1c of the gun barrel 1 is nominal inasmuch as the inside diameter of the tube 2a is only slightly smaller than the inside diameter of the gun barrel 1, thus providing a small pressure differential on the poppet valve 7 in favor of the compressed air inside the pressure cylinder 2.

It will be here noted that when the trigger 12 is pulled, the piston 14 covers the tube 21 preventing escape of air therefrom and further entrance of air into the cylinder 11 from the supply tube 20 so that air cannot leak outwardly from the cylinder 11 through the pressure cylinder 2 and gun barrel 1 when the trigger 12 has been pulled; and when the trigger 12 is released, the spring 23 forces the plungers 13 and 14 into such position that the tube 22 communicating with the air cylinder 8 is shut off from the air pressure supply 20, permitting the spring 10 to force the poppet valve 7 into the position as shown in Fig. 2 of the drawings. The cylinder 8 is vented on one side of the piston 9b by the opening 8a. Air is forced outwardly through the tube 22 at one side of the piston 9b and is vented through the opening 11a in the trigger

valve casing 11. Likewise, the vent 11b operates adjacent the piston 14 for relieving air entering the cylinder 11 due to the pulling of the trigger 12, all as hereinbefore described. It will be noted that the baffle 1b, when the trigger 12 is pulled, deflects the air admitted through the poppet valve 1 upwardly to the upper side of the bottle A which is held in position by the nib 4a of the spring 4 and the neck engaging spring 5. The combination of the nib 4a, the spring 5 and the baffle 1b prevents the bottle A from receiving lateral thrust against the side of the barrel at the edge of the opening 1a which reduces breakage of the bottles leaving the gun to a minimum.

It will be noted that bottles may be shot from the gun barrel 1 in rapid succession by repeatedly opening and closing the sleeve 3 in connection with the handle 15 and pulling the trigger 12a after the sleeve 3 has been closed in each cycle of operation thereof. The sight 19 on the gun barrel 1 affords aiming facility for the operator of the gun and improves generally the accuracy of pointing the same.

It will be here noted that the bottles A are projected base first whereby the neck end thereof faces toward the breech of the gun and these bottles, so projected, withstand higher pressures, and consequently may be projected at higher velocities.

Though I have shown and described a particular construction, combination and arrangement of parts and portions, I do not wish to be limited to this particular construction, combination and arrangement, but desire to include in the scope of my invention the construction, combination and arrangement substantially as set forth in the appended claims.

Having thus described my invention, what I claim as new and desire to secure by Letters Patent is:

1. In a bottle shooting gun of the class described, the combination of a gun barrel, a pressure chamber communicating with the breech end of said barrel, a poppet valve engaging the open breech end of said gun barrel within said pressure chamber and provided with an extending reduced diameter portion, said pressure chamber provided with a hollow, tubular portion slightly smaller in internal diameter than the internal diameter of the bore of said gun barrel, in which hollow tubular portion the reduced diameter portion of said poppet valve is reciprocally mounted and means for retracting said poppet valve away from the open end of said gun barrel longitudinally thereof, said retracting means comprising an air cylinder, secured in connection with said pressure cylinder having a plunger therein connected to said poppet valve for forcing same away from the open end of said gun barrel, a trigger valve for controlling the flow of air pressure to said air cylinder, said trigger valve having a cylindrical casing, a plunger mounted therein having two spaced pistons, an air pressure supply entering said trigger valve casing intermediate said pistons, a tubular conductor extending from a position intermediate said pistons in communication with said pressure cylinder and a second tubular conductor communicating with the interior of said trigger valve casing and said air cylinder adapted to be opened to said pressure supply tube when said pistons in said trigger valve casing are shifted longitudinally thereof, whereby the shifting of said pistons closes off the tubular conductor in-

termediate said trigger valve casing and said pressure cylinder.

2. In a bottle shooting gun of the class described, the combination of a gun barrel, a pressure chamber communicating with the breech end of said barrel, a poppet valve engaging the open breech end of said gun barrel within said pressure chamber and provided with an extending reduced diameter portion, said pressure chamber provided with a hollow, tubular portion slightly smaller in internal diameter than the internal diameter of the bore of said gun barrel, in which the reduced diameter portion of said poppet valve is reciprocally mounted and means for retracting said poppet valve away from the open end of said gun barrel longitudinally thereof, said gun barrel having an opening near the breech end thereof, arranged to admit bottles, a sleeve slidably mounted over said opening and a handle for operating said sleeve, a channel shaped magazine arranged in upwardly and laterally inclined relationship with said opening in said gun barrel arranged to hold a plurality of bottles adjacent said opening in said gun barrel.

25 3. In a bottle shooting gun of the class described, the combination of a gun barrel, a pressure chamber communicating with the breech end of said barrel, a poppet valve engaging the open breech end of said gun barrel within said pres-

30 sure chamber and provided with an extending reduced diameter portion, said pressure chamber provided with a hollow, tubular portion slightly smaller in internal diameter than the internal diameter of the bore of said gun barrel, in which

35 the reduced diameter portion of said poppet valve is reciprocally mounted and means for retracting said poppet valve away from the open end of said gun barrel longitudinally thereof, said gun barrel having an opening near the breech end thereof, arranged to admit bottles, a sleeve slidably mounted over said opening and a handle for operating said sleeve, a channel shaped magazine arranged in upwardly and laterally inclined relationship with said opening in said gun barrel arranged to hold a plurality of bottles adjacent said opening in said gun barrel, a spring loaded nib in connection with said sleeve adapted to engage the side of each bottle when positioned in said gun barrel for holding the same downwardly away from said opening.

45 4. In a bottle shooting gun of the class described, the combination of a gun barrel, a pressure chamber communicating with the breech end of said barrel, a poppet valve engaging the open breech end of said gun barrel within said pressure chamber and provided with an extending reduced diameter portion, said pressure chamber provided with a hollow, tubular portion slightly smaller in internal diameter than the internal diameter of the bore of said gun barrel,

55 in which the reduced diameter portion of said poppet valve is reciprocally mounted and means for retracting said poppet valve away from the open end of said gun barrel longitudinally thereof, said gun barrel having an opening near the breech end thereof, arranged to admit bottles, a sleeve slidably mounted over said opening and a handle for operating said sleeve, a channel shaped maga-

60 zine arranged in upwardly and laterally inclined relationship with said opening in said gun barrel arranged to hold a plurality of bottles adjacent said opening in said gun barrel, a spring loaded nib in connection with said sleeve adapted to engage the side of each of said bottles when posi-

tioned in said gun barrel for holding the same downwardly away from said opening, a spring clip near the breech end of said barrel, for maintaining the neck of said bottle in spaced relationship with the breech of said barrel.

5. In a bottle shooting gun of the class described, the combination of a gun barrel, a pressure chamber communicating with the breech end of said barrel, a poppet valve engaging the open breech end of said gun barrel within said pressure chamber and provided with an extending reduced diameter portion, said pressure chamber provided with a hollow, tubular portion slightly smaller in internal diameter than the internal diameter of the bore of said gun barrel, in which the reduced diameter portion of said poppet valve is reciprocally mounted and means for retracting said poppet valve away from the open end of said gun barrel longitudinally thereof, said gun barrel having an opening near the breech end thereof, arranged to admit bottles, a sleeve slidably mounted over said opening and a handle for operating said sleeve, a channel shaped magazine arranged to hold a plurality of bottles adjacent said opening in said gun barrel, a spring loaded nib in con-

nection with said sleeve adapted to engage the side of each of said bottles when positioned in said gun barrel for holding the same downwardly away from said opening, a spring clip near the breech end of said barrel, for maintaining the neck of said bottle in spaced relationship with the breech of said barrel, whereby pressure exerted from said pressure cylinder on said bottle is exerted on the neck end thereof.
